(57) **CLAIM**

The ornamental design for a case for toy beads as shown and described.

DESCRIPTION

FIG. 1 is a perspective view of a case for toy beads showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a perspective view showing an opened state.

The broken lines in the drawings are for the purpose of illustrating portions of the case for toy beads that form no part of the claimed design.

The dash-dot broken line defines the bounds of the claimed design and forms no part thereof.

1 Claim, 8 Drawing Sheets
